UNITED STATES PATENT OFFICE.

ALBERT E. EHMKE, OF SILVER CREEK, NEW YORK, ASSIGNOR OF ONE-THIRD TO CHARLES W. EHMKE AND ONE-THIRD TO ALBERT B. CHAPMAN, BOTH OF SILVER CREEK, NEW YORK.

SPARK PLUG FOR EXPLOSIVE ENGINES.

Application filed October 14, 1921. Serial No. 507,666.

To all whom it may concern:

Be it known that I, ALBERT E. EHMKE, a citizen of the United States, residing at Silver Creek, in the county of Chautauqua and State of New York, have invented certain new and useful Improvements in Spark Plugs for Explosive Engines, of which the following is a specification.

My invention relates to improvements in 10 spark plugs for explosive engines, and more particularly to what are termed multiple-gap spark plugs.

The primary object of this invention is the production of a spark plug having a 15 plurality of sparking gaps, all of which are preferably exposed so that the explosive fuel delivered to the combustion chamber of the engine to which the spark plug is applied will come in direct contact with the spaced 20 sparking elements forming said gaps.

A further object of my invention is the provision of a spark plug in which a plurality of spark gaps are provided and so arranged to cause a series of intense annular 25 sparks which will effectively ignite the explosive mixture drawn into the engine.

A still further object is to so construct the 30 sparking elements forming the plurality of spark gaps, that fouling of any spark gap of the plurality or series will assure proper 35 operation of the engine, as a single spark gap properly functioning will cause the spark plug to operate as efficiently as the common spark plugs now in use when acting 40 at their highest efficiency; although there will be a reduction from maximum efficiency when any of the spark gaps become foul.

The invention consists in the novel features of construction and in the arrangement 45 and combination of parts to be herein-after described, and more particularly pointed out in the subjoined claims.

In the drawings:—

Figure 1 is a side elevation of a spark 50 plug constructed in accordance with my invention.

Fig. 2 is an enlarged vertical section of the 55 spark plug showing the inner end thereof threaded into an engine cylinder.

Fig. 3 is a detached perspective view of the insulation element carrying one or more 60 of the sparking elements.

Fig. 4 is a detached perspective view of the innermost sparking element and its support.

Fig. 5 is an inverted perspective view of the lower end of the axial electrode which extends through the insulation core, with one of the sparking elements secured thereto.

Fig. 6 is an enlarged transverse section 60 taken on line 6—6, Fig. 1.

In Fig. 2 of the drawing, the numeral 7 designates one of the walls of an engine cylinder into which my improved spark 65 plug is shown threaded.

The spark plug comprises a suitable shell or casing 8 having a porcelain or other insulation core 9 extending therewith, said core being retained in said shell or casing by a nut 10. The core 9 has an enlarged portion 70 11 which bears against a shoulder 12 in the shell or casing, and between the inner end of the nut and said enlarged portion, a gasket 13 is interposed, thus making a tight joint to prevent the escape of gases through the 75 spark plug shell or casing. This, however, forms no part of my invention and the shell or casing and core may be constructed and secured together in any other approved manner.

As is common in spark plug constructions, the porcelain or other insulation core 9 has an electrode 14 extending axially therethrough, the outer end of which projects from the outer or upper end of said core 85 and has the usual clamping nut 15 applied thereto by means of which the terminal of a current wire 16 is secured to the plug.

The porcelain or insulation core 9 terminates at its inner end a short distance from 90 the inner end of the shell or casing 8, and the inner end of said axial electrode is reduced to form an inwardly facing shoulder 17. Said reduced portion is externally threaded, as at 18, onto which is applied a 95 socket 19 which has a central bore threaded through a portion of its length to receive the externally threaded reduced inner end of the electrode 14, said bore being of greater length than the length of said reduced portion so as to receive the inner end of a slender insulation element 20, which may be constructed of lava, mica, or porcelain 100 properly fired. Preferably the inner end

2
of the socket 19 is in a plane outside of the spark plug shell or casing 8. The socket 19, as will appear hereinafter, forms one of the plurality of sparking elements, and may be 5 said to serve as part of the axial electrode 14. The opposite end of the insulation element 20 is fitted into a socket 21, which serves as a sparking element, said socket having a transverse opening 22 therein, 10 through which a yoke 23 formed of wire is passed, said yoke having its ends inserted into sockets 24 formed in the end of the spark plug at diametrically opposite points. The yoke 23 serves as a current-conducting 15 support and comprises a transverse member 25 and side members 26, the transverse member being bent inwardly between its ends, as at 27, thus forming more or less sharply- 20 curved or angular corners at the points of connection of said transverse member to said side members. Therefore, oil accumulating on the cylinder wall or on the edge of the shell or casing of the spark plug may travel 25 inwardly along the side members and drip from the curved or angular portions 28, and as these angular portions are at the innermost points of the yoke, oil is prevented 30 from traveling along the transverse member 25 and reaching the spark gaps, thus preventing fouling of the spark plug; it being assumed of course that in most cases, the spark plug will be used in a vertical position or at only a slight angle to the vertical and that said sharply-curved or angular 35 portions will consequently be the lowest points of the spark plug.

Secured to the slender insulation element 20 is one or more sleeves 29 which serve as 40 sparking elements. In the drawing I have shown two sparking elements 29 secured to the slender insulation element and these are spaced apart. The inner of the two sparking elements 29 is spaced from the socket 21 while the outer is spaced from the socket 19, thus forming a plurality of spark gaps 30 between all sparking elements.

The ends of the yoke 23 are detachably 45 retained within the sockets 24 in the shell or casing, thus permitting the ready removal of the slender insulation element 20 with its attached sleeves 29 from the socket 19, it being simply necessary to pull inwardly on the yoke or support, which will carry the socket or sparking element 21 with 50 it, leaving the insulation member with its 55 sparking elements 29 hanging from the socket 19, unless the upper end of said insulation element has become worn from constant removal and replacement and so loosely fits the socket 19 that it cannot be retained thereby, in which case the insulation element will be withdrawn when removing 60 the yoke and its socket 21.

The spark gaps 30 are of circular or angular 65 formation and extend around the in-

sulation element 20, thus when current is passed through the spark plug, a series of circular sparks are created, which extend from the sparking element to an adjacent 70 sparking element, thereby providing intense and extensive sparks, which will assure powerful explosion of the explosive mixture within the engine cylinder.

The device shown and described is simple, inexpensive, and highly efficient, and assures proper operation of a motor under all running conditions, as the fouling of any spark gap or gaps less than the total number employed, will merely reduce the efficiency without effecting the smooth running of the engine and as constructed, the spark plug can be easily cleaned without resorting to the removal of the core and other parts of the plug, as invariably necessary in spark plugs now in use.

Having thus described my invention, what I claim is:—

1. A spark plug comprising a shell or casing, an insulation core having a portion thereof held within said shell or casing and extending from one end thereof, an electrode extending axially through said core and projecting from opposite ends thereof, one end of said electrode being adapted to have a current-conducting wire attached thereto, a socket secured to the other end thereof, a slender insulation element having one end held within said socket, a support secured to the inner end of said shell or casing, a socket carried by said support and having the other end of said slender insulation element held therein, and a sparking element on said slender insulation member between said sockets and spaced therefrom to provide a plurality of spark gaps.

2. A spark plug comprising a shell or casing, an insulation core extending into and secured to said shell or casing, an electrode extending axially through said core and projecting inwardly beyond the inner end of said shell or casing, a wire support comprising a transverse member and two side members and having its free ends secured in the inner end of said shell or casing, a slender insulation element receiving support from said electrode and said support, and a plurality of sparking elements on said slender insulation element spaced from each other to provide a sparking gap or gaps.

3. A spark plug comprising a shell or casing, an insulation core extending into said shell or casing, an electrode extending axially through said insulation core, a current conducting support secured to the lower end of said shell or casing, and a sparking element between and carried by said electrode and said current conducting support.

4. A spark plug comprising a shell or casing, an insulation core held therein, an electrode extending through said core and hav-

- ing an externally-threaded reduced inner end, a socket threaded onto the reduced inner end of said electrode, a U-shaped member formed of wire having opposite ends secured into the inner end of said shell or casing, a socket arranged centrally on said U-shaped member in line with the socket on said electrode, an insulation element having opposite ends held in said sockets, and a 10 sparking element secured to said insulation element.
5. A spark plug comprising a shell or casing, an insulation core extending centrally into said shell or casing, an electrode extending axially through said insulation core, a support formed of wire having a transverse member and two side members arranged at an angle to said transverse member, said side members having their ends entered into said 15 shell or casing at the inner end thereof and having its transverse member bent inwardly from its intermediate portion, a socket having a transverse opening through which the transverse member of said support is passed, 20 a socket secured to the inner end of said electrode, a slender insulation element having opposite ends entered in said sockets, and 25 sparking elements on said insulation mem-
- ber spaced apart to provide spark gaps with the sparking elements adjacent said sockets 30 spaced therefrom to provide additional spark gaps.
6. A spark plug comprising a shell or casing having sockets in its inner end at diametrically opposite points, a substantially 35 U-shaped support formed of wire having opposite ends entered in said sockets, an insulation core secured within said shell or casing, an electrode extending axially through said insulation core, a socket secured to the inner end of said electrode, a socket on said support having its axis coincident with that of the socket secured to said electrode, a slender insulation member having opposite ends entered in said sockets, 40 and sleeves carried by said slender insulation member and being spaced apart, the sleeve adjoining the socket on said electrode being spaced therefrom and the sleeve adjoining the socket on said support being 45 spaced therefrom, the spaces between said sleeves and between said sleeves and said 50 socket forming spark gaps.

In testimony whereof I affix my signature.

ALBERT E. EHMKE.
